(57) **CLAIM**

The ornamental design for a stackable wine rack, as shown and described.

DESCRIPTION

FIG. 1 is a perspective view of a stackable wine rack showing our new design;

FIG. 2 is a top plan view thereof;

FIG. 3 is a front elevational view thereof;

FIG. 4 is a right side elevational view thereof, the left side elevational view being identical;

FIG. 5 is a bottom plan view thereof;

FIG. 6 is a perspective view of a second embodiment of the design shown in FIG. 1, showing a three-tier wine rack formed of three stacked wine racks of FIG. 1, it being understood that more or less tiers may be provided by stacking the racks of FIG. 1;

FIG. 7 is a top plan view thereof;

FIG. 8 is a front elevational view thereof;

FIG. 9 is a right side elevational view thereof, the left side elevational view being identical;

FIG. 10 is a bottom plan view thereof; and,

FIG. 11 is a perspective view showing of the three tier wine rack of FIG. 6 having an indeterminate width and identically space as in FIG. 6.
